[57] CLAIM

The ornamental design for an insulated bottle carrier, as shown and described.

DESCRIPTION

FIG. 1 is a front elevational view of an insulated bottle carrier showing my new design, the opposite side being identical;

FIG. 2 is a top plan view thereof;

FIG. 3 is a side elevational view thereof;

FIG. 4 is a front elevational view of an alternate embodiment of FIG. 1, the opposite side being identical;

FIG. 5 is a top plan view of FIG. 4; and,

FIG. 6 is a side elevational view of FIG. 4.

The undisclosed bottom views are unornamented. The broken line showing of the bottle is for illustrative purposes only.

Fig. 2.

Fig. 1.
